INTERNAL-COMBUSTION ENGINE

Rudolph Daub, West Caldwell, N. J.

Application December 22, 1944, Serial No. 569,317

5 Claims. (Cl. 123—73)

1

This invention relates to 2-cycle internal combustion engines and particularly to such engines in which the pistons are paired, each pair being connected to a single crank pin.

The main object of the invention is an engine of this type containing features and characteristics conducive to more economical manufacturing methods.

Another object is an engine, the structure of which permits the extensive use of light alloy die castings.

Another object is an improved cylinder, gas tank, needle valve and ignition timer arrangement especially adaptable to miniature model engines such as used in toy airplanes, boats and racing cars.

Other objects will be apparent in the following specifications and drawings showing a preferred form of the invention in which

Fig. 1 is a longitudinal section through the engine assembly taken at the line 1—1 of Fig. 2;

Fig. 2 is a cross section through the engine taken at the line 2—2 of Fig. 1;

Fig. 3 is a top view of the cylinder head;

Fig. 4 is a fragmentary section showing the gas transfer channel connecting the crankcase with the cylinder intake ports and taken on line 4—4 of Fig. 2;

Fig. 5 is a section through the crankcase intake port belt taken on line 5—5 of Fig. 2;

Fig. 6 is a section through the cylinder intake and cylinder exhaust port belts taken on line 6—6 of Fig. 2;

Fig. 7 is a front view of a gasket structure; and

Fig. 8 is a fragmentary front view of the engine with the cover and gasket removed.

Referring to Figs. 1 and 2, 10 is the cylinder and crankcase housing case in one piece providing cylinders 55, 56 and crankcase 57. At 11 is seen a boss forming the bearing for the shaft 12 of the rear crankshaft assembly 13. At portion 14 of the shaft is fastened a cam 15 adapted to operate an ignition timer 16 in the conventional manner.

Rear crankshaft assembly 13 consists in addition to shaft 12 of a crankcheek 17 having a bore 18 which fits crankpin 19 of front crankshaft assembly 20 and thereby has the motion of the front crankshaft imparted to it. Rear shaft 12 has a notch 21 into which the material of die-cast cheek 17 flows thereby providing a positive torque transmitting device besides confining the cheek in its correct axial position on shaft 12.

Fabricated in a similar manner is front crankshaft 20, i. e., crankpin 19 and front shaft 22 and

2

counterweight 23 are placed in a metal die having a cavity in the shape of front crankcheek 24. The metal poured into this cavity will combine these separate pieces into a tightly gripped one piece assembly. To absolutely insure this grip slot 25 and hole 26 are provided in the cheek, the latter one to receive a clamp bolt 27. Positive axial location is maintained by notches in crankpin 19 and shaft 22, both notches partially embracing clamp bolt 27.

Counterweight 23 is a steel or brass stamping and is provided with holes 29, the holes, being filled by the metal during the casting process, forming the means for retaining the counterweight within its confines of the crankcheek 24.

By the aforesaid means and method a very sound crankshaft can be fabricated very economically, requiring a minimum amount of machining, because for both crankpin and shaft 20 commercial drill rod stock, which is made to very close tolerances and marketed at a low price, can be employed, limiting the machining operations for the entire shaft to cutting threads 28 only, said thread to receive a nut retaining the propeller, flywheel or the like.

The housing 10 has a flat face 129 coinciding with line 8—8 on Fig. 1, the face being of a shape as seen in Fig. 8. Terminating at said face 129 are crankcase intake port belt 30, cylinder intake port belt 31 and cylinder exhaust port belt 32. In communication with these port belts are the holes 33 of the cylinder sleeves 34, said cylinder sleeves being inserted into bores of crankcase and cylinder housing 10. The upper edge of one piston 60 times the opening and closing of the cylinder intake ports at belt 31, the upper edge of the other piston 61 that of the cylinder exhaust ports at belt 32, while the lower edges of both pistons 60, 61 time the opening and closing of the crankcase intake ports at belt 30.

Also terminating in face 129 is gas and air inlet conduit 35 located in between the cylinders and in communication with crankcase intake port belt 30 on one side and air inlet bore 36 on the other side, said air inlet bore being part of cover 37, as best seen in Figs. 1 and 5. Coaxial with said air inlet bore 36 is located needle 38, the pointed portion of the needle serving as a valve for gasoline jet hole 39. This jet hole is located in vertical gasoline conduit 40 the inner end of the conduit being in open communication with the interior of fuel tank 41. Needle valve 38 is operable by turning screw knob 42 in the conventional manner. This novel arrangement eliminates all outside piping and the danger of break-

age of it and considerably contributes to a clean and compact appearance of the whole engine assembly.

During the operation of the engine the vacuum created in the crankcase by the outgoing pistons causes air to be drawn through air intake hole 36 the moment the lower piston edges uncover the sleeve ports which are in communication with the crankcase air inlet belt 30. This air rushes past the gasoline jet hole 39 at a high velocity and under a partial vacuum causing the gasoline to be drawn from the tank 41 up through conduit 40 and out the jet 39 where on its way to the crankcase it is mixed with the air and thereby forming a combustible mixture. The ingoing pistons compress this mixture up to the time the upper edge of the intake piston uncovers the holes 33 in the intake cylinder sleeve which are in communication with the cylinder intake port belt 31, when the compressed mixture is allowed to enter the cylinder for scavenging via the connection between intake port belt 31 and the crankcase, formed by transfer channel 44 as best shown in Figs. 4, 7, 5, 6 and 8. Exit of the burnt gases from the cylinder occurs through the sleeve ports which are in connection with cylinder exhaust belt 32 and exhaust pipe 45 as best indicated in Fig. 5.

Cover 37 has integrally connected to it a bearing extension 45, the connection being strengthened by ribs 46. The bearing extension has a bushing 47, the bushing being held by means of a threaded nut 48 which nut also acts as a retainer for fuel tank 41, with gaskets 49 and 50 forming the seals. Fuel hose 51 connected to conduit 40 reaches to the bottom of the tank with a length S for upright engine installation and length L for inverted engine installation. In the latter case, tank 41 must be rotated 180° so as to maintain a top location for filler cap 52.

Located between face 429 of crankcase and cylinder housing 10 and the mating face of cover 37 is a gasket member 53. This member besides fulfilling its functions as a seal is perforated in such a manner as to form a partition for transfer channel 44 as best seen in Fig. 5. It also provides a seal between exhaust port belt 32 and inlet belts 30 and 31. This design permits casting of all port belts in the crankcase and cylinder housing 10 and also the transfer channel in cover 37 to be accomplished without resorting to coring and thereby rendering a design capable of being die-cast by means of metal molds by high speed, low cost, mass-production methods.

Cylinder head 54 shown in Fig. 3 is secured to housing 10 by screw fastenings 43 and provides the spark plug opening 59 at the center of the combustion space. Piston 60 is connected to the crankpin 49 by master connecting rod 63 joined to the master rod 62 at pivot 64.

Although a specific embodiment of the invention has been illustrated as adapted to a dual cylinder design, it will be apparent that the invention could be adapted to a single cylinder construction and that various other alterations in the

details of construction may be made without departing from the scope of the invention as indicated by the appended claims.

For instance, in Diesel operation of the engine, the usual injector will replace the spark plug in opening 59. Various sizes of engines may be built although the form shown is particularly adapted for small powers. With a piston diameter of one inch the dual cylinder unit shown develops about three horsepower.

I claim:

1. An internal combustion engine comprising a housing having a pair of cylinders in U-formation transverse to the shaft, a cover for said housing having an air intake opening, a needle valve between said cylinders and having its end in said air intake opening to control the air and fuel mixture.

2. In a 2-cycle internal combustion engine, a casting formed with a plurality of cylinders, liners for said cylinders having ports for the passage of gases, belt passages in said casting completely around each of said liners at said ports and having parallel sides extending to a face of said casting, and a cover plate fastened to said face of said casting over said passages.

3. A 2-cycle internal combustion engine as set forth in claim 2 in which one of said belt passages is an intake and the adjacent belt passage is an exhaust.

4. An internal combustion engine comprising a cylinder and crankcase housing formed by an integral casting and having a transverse face providing fuel passage openings, a cover means for said face forming a wall for a fuel passage of said casting and provided with a fuel supply reservoir around a portion of the crankshaft, and a crankshaft journaled in said casting and said cover means.

5. In an internal combustion engine a casting formed with a plurality of cylinders, liners for said cylinders having ports for the passage of gases, belt passages around each of said liners in said casting and extending to openings at the face of the casting on one side thereof, a cover fastened to said face over said passages and providing a closure for one of said openings and a conduit for another, and a fuel intake carried by said cover.

RUDOLPH DAUB.
